UNITED STATES PATENT OFFICE.

FREDERICK J. EDGARS, OF BROOKLYN, NEW YORK.

DESIGN FOR A BOX.

SPECIFICATION forming part of Design No. 23,851, dated December 4, 1894.

Application filed October 31, 1894. Serial No. 527,586. Term of patent 7 years.

To all whom it may concern:

Be it known that I, FREDERICK J. EDGARS, a citizen of the United States, residing at Brooklyn, in the county of Kings and State of New York, have invented and produced a new and original Design for a Wooden Box, of which the following is a specification.

In the drawing I have represented my design by an elevation and partial section.

10 The general configuration of the box is round, and the leading features of my design consist in the plain tapering central portion with rounded base and the bands, ribs and coves at the respective ends.

15 The design of the cover A comprises the flat top *a*, slanting portion *b*, plain rib *c*, round rib *d*, curved rib *e*, cove *f*, double band *g* and plain tapering portion *h*.

The design of the body portion B comprises the plain tapering portion *h'*, a continuation ²⁰ of the portion *h* of the cover and rounded at the lower part, the curved band *i*, the double inclined rib *k*, the curved bands *l*, and the curved base rib *m*.

What I claim is—

25 The design for a wooden box substantially as shown and described.

Signed by me this 29th day of October, A. D. 1894.

FREDERICK J. EDGARS.
